UNITED STATES PATENT OFFICE.

CHARLES T. HEISEL, OF CLEVELAND, OHIO.

DESIGN FOR A HEATING-STOVE.

SPECIFICATION forming part of Design No. 18,179, dated March 13, 1888.

Application filed February 3, 1888. Serial No. 262,941. Term of patent 7 years.

To all whom it may concern:

Be it known that I, CHARLES T. HEISEL, a citizen of the United States, residing at Cleveland, in the county of Cuyahoga and State of Ohio, have invented and produced a new and original Design for Stoves, of which the following is a specification, reference being had to the accompanying drawing, forming a part thereof.

10 The figure is a perspective view of a stove showing my design.

The leading feature of my design consists of a mica paneled dome top to a stove; and it consists of a half spherical top in continuation of the body, and providing the same with mica panels in like manner to and as a continuation of lights to those of the body.

15 A represents the base of a stove; B, the body. These contain the fire-pot, flues, ash-pit, and other parts usually appertaining to stoves. The body B is cylindrical in its general contour, and is provided with doors having mica panels.

D is a dome, which is hemispherical in its general contour and composed of mica panels, which present a continuation of mica panels 25 from the body to the apex of the dome, and may be surmounted with a cover or lid, C, having a vase or other suitable ornamental finial sitting over a central opening in the apex.

30 Having described my invention, I claim—

1. In a design for a stove herein shown and described, the dome consisting of a half-spherical frame having mica panels, substantially as specified.

35 2. In a design for a stove herein shown and described, the same consisting of a dome, D, provided with mica panels, a cylindrical body, B, and a rectangular base, A, all substantially as set forth.

CHARLES T. HEISEL.
